[57] CLAIM

The ornamental design for jaw cover for surgical clamp
or the like, as shown and described.

DESCRIPTION

FIG. 1 is a top plan view of jaw cover for surgical
clamp or the like showing my new design;

FIG. 2 is a side elevational view thereof;

FIG. 3 is a bottom plan view thereof;

FIG. 4 is an end elevational view of the open end
thereof;

FIG. 5 is a cross-sectional view taken on line 5—5 of
FIG. 1;

FIG. 6 is an end elevational view of the closed end
thereof;

FIG. 7 is an enlarged representation of FIG. 5.

FIG. 1

FIG. 2

FIG. 3
